UNITED STATES PATENT OFFICE.

AMANDA T. JONES, OF CLINTON, WISCONSIN.

IMPROVEMENT IN FRUIT-JARS.

Specification forming part of Letters Patent No. **140,508**, dated July 1, 1873; application filed June 10, 1873.

To all whom it may concern:

Be it known that I, AMANDA T. JONES, of Clinton, in the county of Rock and State of Wisconsin, have invented a new and valuable Improvement in Preserving-Jars; and I do hereby declare that the following is a full, clear, and exact description of the construction and operation of the same, reference being had to the annexed drawings making a part of this specification, and to the letters and figures of reference marked thereon.

Figure 1 of the drawings is a representation of a sectional view of my invention. Fig. 2 is a view of the top of my jar. Figs. 3, 4, 5, 6, 7, 8, and 9 are details of this invention.

This invention has relation to preserving-jars for fruit and other articles; and it consists in the construction and novel arrangement of two horizontal beads or flanges of different diameters at the neck of the jar, one above the other, each provided with flattened faces or recesses diametrically opposite to each other; of a concavo-convex cover having within its rim certain swells or cord-like faces adapted to fit the flattened external faces or depressions of the upper flange of the jar; of the cam-like curvatures of the clamping-bar in the portion surrounding the central opening, whereby this portion is raised at the narrower diameters, and depressed as the bar broadens; of the internal shelf or ledge within the central opening for the reception of a packing-ring; of a concave cap-plate adapted to press upon said packing-ring, and provided with two hooked ends adapted to engage with the cam-curves of the clamping-bar; and in connection with said clamping-bar, and the internal swells of the cover, of certain cam-like rises or swells of the convex top, making it higher at points at right angles with said internal swells.

In the accompanying drawings, the letter A designates the upper portion of a jar, having at its neck two horizontal beads or flanges, B and C, one of smaller diameter than, and lying above, the other, said flanges being each flattened or recessed, respectively, at the points *b* and *c*, diametrically opposite each other, as shown in Fig. 2 of the drawings. D indicates a concavo-convex cover provided on the inside of its rim, at diametrically-opposite points,

with the internal swells or segments *a*, adapted to fit the faces *b* of the upper flange of the jar, and thus serving to steady the cover, keeping it from rotating on the jar. The convex top of the jar is provided with cam-like rises or swells *d d* at points ninety degrees distant from the internal swells *a*, for the purpose of tightening the clamping-bar when the latter is engaged with the lower flange C, and turned upon said convex top. The cover is centrally perforated at *e* and provided with an annular rise or lip, *f*, surrounding the aperture, and within it with an internal ledge, *g*, adapted to receive a packing-ring, *h*. E represents the clamping-bar, a bent metal plate having an opening, F, in its center, through which the annular projection or lip *f* passes, and hooked ends *G*, adapted to engage with the lower flange of the jar. Those portions *z* of the plate on each side of the opening F are curved outward and downward, forming cams highest at the smallest diameters *y y* and lowest at the largest diameters *x x*, adapted to engage with the hooked ends *n* of the concave cap-plate H in such a manner that as said cap-plate is turned on a vertical axis its hooked ends are drawn downward by the cam-curves *z*, forcibly depressing the plate on the packing-ring *h* of the central opening.

The operation of closing the jar or can is as follows: A large packing-ring, *k*, having been placed on the upper surface of the lower flange C of the jar, the convex cover is placed thereon in the only position in which it will fit—that is, with the internal cord-faces in contact with the flattened faces of the upper flange. The clamping-bar is then placed over the cover, its hooked ends passing readily down by the flattened faces or recesses *c* of the lower flange. It is then turned through an angle of ninety degrees, bringing its hooked ends into engagement with said lower flange, and its middle portion or body into engagement with the swells or cam-rises of the convex top, thus securing it tightly.

For some purposes this closing is sufficient, the central aperture F and the cap-plate being dispensed with. In other cases, as when the exhaustion of air forms a part of the preserving process, the central aperture is preferred, and it is closed as follows: The rubber ring

or packing having been placed on the internal ledge g the cap-plate H with its convexity downward is placed thereon, its hooked ends being in line with one of the smaller diameters $y y$ of the open portion of the bar. The cap-plate is then turned horizontally, its hooked ends engaging with the cam-curves z of the bar, and thus gradually depressing the cap-plate until the largest diameter $x x$ is coincident with the position of said hooks. At these points of the curves straight edges v are preferably provided to steady the hooked ends n so that the reacting pressure of the rubber and the elastic plates will not cause the cap-plate to turn back on the cam-curves z and loosen the joint.

What I claim is—

1. A secondary flange, B , above the clamp-flange C , having the flat faces or recesses b , substantially as specified.
2. A concavo-convex cover having the internal segments or swells a within its rim, substantially as specified.

3. The annular packing-shelf g within the central opening e , substantially as specified.

4. A clamping-bar, open in its middle portion, and provided with the outward and downward cam-curves z , substantially as specified.

5. A clamping-bar, open in its middle portion, and provided with the outward and downward cam-curves z , terminating in straight edges u , substantially as specified.

6. A cap H , concave in form, and provided with the downward-hooked ends n , substantially as specified.

7. The combination of the double-flanged jar, the concavo-convex and centrally-perforated cover, the packings h and k , the clamping-bar E , the cams z , and the hooked cap-plate H , substantially as specified.

In testimony that I claim the above I have hereunto subscribed my name in the presence of two witnesses.

Witnesses: AMANDA T. JONES.

PHIL. C. MASI,
GEO. H. MILLER.
